UNITED STATES PATENT OFFICE.

JAMES Y. BOWSER AND EMERY P. BOWSER, OF KITTANNING, PENNSYLVANIA.

CLAMP

1,101,396.

Specification of Letters Patent. Patented June 23, 1914.

Application filed March 21, 1914. Serial No. 826,459.

To all whom it may concern:

Be it known that we, JAMES Y. BOWSER and EMERY P. BOWSER, citizens of the United States, residing at Kittanning, in the county of Armstrong and State of Pennsylvania, have invented certain new and useful Improvements in Clamps, of which the following is a specification.

This invention relates to an improved clamp which is intended to be placed about a finished pipe before the pipe is placed in a vise so that the pipe will be prevented from being marred or injured by the vise jaws when the jaws are tightened.

15 The principal object of the invention is to so connect the two sections of the clamp that they will be slidably and pivotally connected together and thus adjusted according to the size of the pipe.

20 Another object of the invention is to so connect the two sections of the clamp that the sections will not contact at one side when in an operative position.

This invention is illustrated in the accompanying drawings wherein—

Figure 1 is a view showing the clamp applied to a pipe which is shown in section and positioned between the jaws of a vise, the jaws being broken away; Fig. 2 is a top plan view of the structure shown in Fig. 1 with the pipe removed; Fig. 3 is a view of one of the sections of the clamp.

The clamp comprises the two sections 10 which are curved transversely so as to 35 form to the contour of the pipe 11 and have their engaging faces covered with fabric strips 12 which are secured to the sections 10 by any suitable means. Ears 13 extend from the lower edges of the sections 10 and are 40 provided with longitudinally-extending slots 14 so that a pin 15 may be passed through the ears 13. These ears 13 are placed in the relation shown in Fig. 2 and it will thus be seen that the two sections may be drawn 45 apart by a sliding movement and may also be moved pivotally. It will also be noted that the ears 13 are provided with flat lower faces so that if the clamp is placed in a flat vise, the ears will form a flat support 50 gaging face for the clamp.

When using this clamp, it is placed about the pipe 11 and is then placed between the

jaws 16 of the vise. The jaws are then brought together and the pipe can be prevented from turning without any danger of 55 its being marred or bent. It is obvious that if the clamp is placed in a vise having vertically moving jaws instead of horizontally moving jaws as shown in the drawings, the clamp will be turned to extend at right 60 angles to the position shown in Fig. 1 with the ears 13 extending vertically instead of horizontally.

We have thus provided a pipe clamp which can be adjusted by sliding and pivotal movement, and which is so constructed that the pipe may be securely held in a vise without danger of the pipe being injured.

What is claimed is:

1. A clamp comprising a pair of sections, 70 hinge ears extending from said sections and provided with longitudinally - extending slots, and a pin passing through the slots of said hinge ears to slidably and pivotally connect said sections.

2. A clamp comprising a plurality of sections provided with curved pipe-engaging faces, cushion means upon the pipe-engaging faces of said sections, ears extending from said sections and provided with longitudinally - extending slots, and a pin passing through said slots to slidably and pivotally connect said sections.

3. A clamp comprising a plurality of sections, ears extending from said sections, and means for slidably and pivotally connecting said sections.

4. A clamp comprising a plurality of sections, and means for slidably and pivotally connecting said sections.

5. A clamp comprising a plurality of sections, and means for slidably and pivotally connecting said sections whereby when said clamp is in a closed position the sections will be in spaced relation at one side of said 95 clamp and in contacting relation upon the opposite side of said clamp.

In testimony whereof we affix our signatures in presence of two witnesses.

JAMES Y. BOWSER.
EMERY P. BOWSER.
